CLAIM

The ornamental design for a starting fluid valve assembly for diesel starting systems, as shown and described.

DESCRIPTION

FIG. 1 is a top plan view of our new starting fluid valve assembly for diesel starting systems;

FIG. 2 is a front elevational view thereof;

FIG. 3 is a side elevational view thereof;

FIG. 4 is a rear elevational view thereof; and

FIG. 5 is a bottom plan view thereof.

A side elevational view taken from the side opposite that shown in FIG. 3 is essentially a mirror image thereof.
